US0D1060953S

(12) United States Design Patent (10) Patent No.: US D1,060,953 S
(45) Date of Patent:  Feb. 11, 2025

(54) SHOE

(71) Applicant: NIKE, Inc., Beaverton, OR (US)

(72) Inventors: Toussaint King, Westerville, OH (US);
Tate E. Kuerbis, Portland, OR (US)

(73) Assignee: NIKE, Inc., Beaverton, OR (US)

() Term: 15 Years

(21) Appl. No.: 29/888,520

(22) Filed: Mar. 31, 2023

(51) LOC (15) Cl. 02-04

(52) U.S. Cl.

USPC D2/972

(58) Field of Classification Search

(57) CLAIM

The ornamental design for a shoe as shown and described.

DESCRIPTION

FIG. 1 is a rear perspective view of a shoe showing our new design;

FIG. 2 is a side view thereof;

FIG. 3 is a front perspective view thereof;

FIG. 4 is an opposite side front perspective view thereof;

FIG. 5 is an opposite side view thereof; and,

FIG. 6 is an opposite side rear perspective view thereof. The broken lines depicting the remainder of the shoe form no part of the claimed design.

1 Claim, 6 Drawing Sheets
